UNITED STATES PATENT OFFICE.

BENJAMIN J. GREER, OF POYNOR, TEXAS.

LOCK.

Application filed December 14, 1921. Serial No. 522,242.

To all whom it may concern:

Be it known that I, BENJAMIN J. GREER, a citizen of the United States, and resident of Poynor, in the county of Henderson and 5 State of Texas, have invented certain new and useful Improvements in Locks, of which the following is a full, clear, and exact description.

My invention relates to combination locks, 10 and one of the objects of my invention is to provide a lock of this character which is most simple in construction, and hence inexpensive in manufacture.

Another object of the invention is to provide 15 a combination lock which is entirely safe, and which is capable of almost an infinite number of combinations.

Further objects and advantages of the invention will appear as the description proceeds. 20

For a complete illustration of the invention reference is to be had to the accompanying drawings, in which;

Figure 1 is a perspective view of the lock 25 in closed position.

Figure 2 is a vertical sectional view taken through the lock.

Figure 3 is a horizontal sectional view taken on line 3—3 of Figure 2, and showing 30 the locking screw as engaging the shackle.

Figure 4 is a view similar to Figure 3, but showing the shackle released from the locking screw.

Figure 5 is a vertical sectional view taken 35 on line 5—5 of Figure 4, and showing the shackle in elevation in closed position, and in broken lines in open position.

Figure 6 is a side view of a slightly modified form of the invention.

Figure 7 is a transverse section of the modified form of the invention, and taken 40 on line 7—7 of Figure 6, and,

Figure 8 is a detail sectional view showing 45 how the locking screw is keyed on the spindle.

Referring to the drawings more in detail, 50 numeral 1 refers to the body of the lock, which is adapted to receive the two legs 2 and 3, of the shackle 4. The shackle is passed through the lock body, and the end 55 of the longer leg is swaged as indicated by numeral 5, to prevent it being entirely withdrawn from the lock body. Flanges 6 and 7 are provided on the legs of the shackle to completely cover the openings in the lock body when the shackle is in locked position.

Each leg of the shackle is provided with a plurality of grooves 8, and preferably these grooves are screw-threaded as shown. In the present instance we have shown three 60 grooves in each leg, but it will be obvious from the description hereinafter that two of the grooves will be sufficient for most purposes.

Passing transversely through the lock 65 body and screw threadedly engaging the lock body and the notches in the shackle, are three locking screws 9, having finger knobs 10 or other means for rotating them. It will be understood, of course, that if only 70 two notches are provided in the legs of the shackle then only two locking screws will be employed. The locking screws are swaged, as indicated by numeral 11, to prevent the withdrawal thereof, and each of 75 the locking screws is provided with two grooves indicated by numeral 12. An inspection of Figure 3 will clearly show how the locking screws engage the grooves provided in the shackle legs 2 and 3, and thereby prevent the withdrawal of the shackle; while Figure 4 shows another position of the locking screw, wherein the grooves in the locking screw are in proper position relative to the shackle to permit the withdrawal 80 of the latter.

It is believed that the operation of the lock will be obvious from the above description. When the shackle is to be locked it is pushed in and the locking screws rotated 90 thereby engaging the grooves in the shackle and preventing its withdrawal. Now when it is desired to release the shackle, each of the locking screws is rotated the necessary number of turns to bring the grooves of the 95 locking screws into alignment with the shackle, and thereby releasing the latter. Of course if preferred, indicia may be employed in any desired manner to assist in getting the exact combination.

It is to be noted here that in order to bring the grooves of the locking screws in such relation to the shackle as to release the latter, it is necessary that two conditions be fulfilled; first, there must be sufficient translation of the screw to bring the grooves into alignment with the legs of the shackle; and second, the screw must then be rotated just sufficiently to bring the grooves into the proper radial position with relation to the 110 shackle legs.

Of course if only one locking screw was

- employed it would be possible to release the shackle by trial, and without knowing the combination; but when two locking screws are employed it is obvious that it would be necessary to know the combination in order to release the shackle. Therefore it is to be understood that while I have shown three locking screws, two such screws will provide a perfectly safe lock, and it is therefore not my intention to be limited to the use of three locking screws. And on the other hand it may be that I would prefer to use more than three locking screws in some instances.
- 15 With reference to the modification shown in Figures 6, 7 and 8, the shackle remains the same as previously described, and the only difference is in the manner of moving the locking screws. In this form I employ 20 three spindles 13, which are rotatably mounted in the lock body, but which have no longitudinal movement therein. Keyed on the spindles 13 are the locking screws 14, which are the same in construction as those previously described. The spindles are swaged at one end 15, and are provided with finger knobs 16 at the opposite ends.
- 25 The key connection between the spindle and the lock screw causes the lock screw to 30 rotate with the spindle, but permits the lock screw to travel longitudinally of the spindle, and the grooves are thus brought into their releasing position in the same manner as before described.
- 35 Having fully described my invention, what I claim as new and desire to secure by Letters Patent is:
- 40 1. A lock including a body and a slid-
able shackle, the shackle being provided with a groove, and a locking screw adapted to en-

gage said groove, said locking screw also being provided with a groove, whereby the shackle is released when the groove on the locking screw is aligned with the shackle.

2. A lock including a body and a slid-
able shackle, a plurality of grooves provided in 45 each leg of the shackle, and a plurality of locking screws adapted to engage said grooves, each of said locking screws provided with two grooves, whereby the shackle 50 is released when the grooves of the locking screws are aligned with the legs of the shackle.

3. A lock including a body and a slid-
able shackle, said shackle being provided with a 55 groove, a spindle rotatably mounted in the body, and a locking screw keyed on said spindle and adapted to engage said groove.

4. A lock comprising a body and a slid-
able shackle, each leg of said shackle being 60 provided with a plurality of grooves, a plu-
rality of spindles rotatably mounted in the body, a locking screw keyed on each of said spindles and adapted to engage said grooves, 65 and grooves also provided in said locking screws, whereby the shackle is released when the grooves of the locking screws are aligned with the shackle.

5. A lock including a body and a slid-
able shackle, said shackle provided with a groove, 70 a locking member engaging said groove, said locking member also provided with a groove, said grooves adapted to align to release the shackle, the locking member being screw-
threadedly engaged in the body whereby the 75 alignment of the grooves depends on both the longitudinal and angular position of the locking member.

BENJAMIN J. GREER.
